(57) **CLAIM**

The ornamental design for an arch cushion as shown and described.

DESCRIPTION

FIG. 1 is a front view of an arch cushion showing my new design according to a first embodiment.

FIG. 2 is a rear view of the arch cushion of FIG. 1.

FIG. 3 is a top view of the arch cushion of FIG. 1.

FIG. 4 is a bottom view of the arch cushion of FIG. 1.

FIG. 5 is a first side view of the arch cushion of FIG. 1.

FIG. 6 is a second side view of the arch cushion of FIG. 1.

FIG. 7 is a top, front, and first side perspective view of the arch cushion of FIG. 1.

FIG. 8 is a bottom, rear, and first side perspective view of the arch cushion of FIG. 1.

FIG. 9 is a cross-sectional view taken along line 9-9 of FIG. 3.

FIG. 10 is a cross-sectional view taken along line 10-10 of FIG. 3.

FIG. 11 is a front view of an arch cushion showing my new design according to a second embodiment.

FIG. 12 is a rear view of the arch cushion of FIG. 11.

FIG. 13 is a top view of the arch cushion of FIG. 11.

FIG. 14 is a bottom view of the arch cushion of FIG. 11.

FIG. 15 is a first side view of the arch cushion of FIG. 11.

FIG. 16 is a second side view of the arch cushion of FIG. 11.

FIG. 17 is a top, front, and first side perspective view of the arch cushion of FIG. 11.

FIG. 18 is a bottom, rear, and first side perspective view of the arch cushion of FIG. 11.

FIG. 19 is a cross-sectional view taken along line 9-9 of FIG. 13; and,

(Continued)

FIG. 20 is a cross-sectional view taken along line 10-10 of FIG. 13.
